United States Patent Office.

ISAAC JUDSON, OF NEW HAVEN, CONNECTICUT.

Letters Patent No. 66,028, dated June 25, 1867.

IMPROVED HYDRAULIC-PRESSURE REGULATOR.

The Schedule referred to in these Letters Patent and making part of the same.

TO ALL WHOM IT MAY CONCERN:

Be it known that I, ISAAC JUDSON, of the city and county of New Haven, in the State of Connecticut, have invented a new and useful Improvement in Hydraulic Regulators; and I do hereby declare that the following is a full, clear, and exact description of the construction, character, and operation of the same, reference being had to the accompanying drawings, which make part of this specification, in which—

Figure 1 is a section cut through the centre in the direction of the induction and eduction pipes, showing the relative positions of the valves, diaphragms, rings, &c.

Figure 2 is a perspective view of one of the flat rings or annular disks used for varying the relative pressure.

My improvement consists in constructing the regulator with one valve, to the stem of which I attach two elastic diaphragms, of different extent of bearing surface, so that the water, which enters the smaller apartment through the induction pipe, may first act upon the smaller diaphragm, the effect of which will be to open the valve and allow the water to pass into the other apartment, so as to press upon the other or larger diaphragm, the tendency of which will be to close the valve, and therefore to regulate the pressure at the eduction pipe by the pressure at the induction pipe, modified by the difference of the surfaces of the two diaphragms, which may be carried to any desired extent by the use of flat rings or annular disks.

I make the main frame of cast iron, or any other suitable material, substantially in the form or shape indicated in section at A A, fig. 1, with an induction pipe or passage, as indicated at B, and an eduction pipe or passage, as indicated at C, and a proper seat for the valve, as indicated at g g. On one side of this frame I fit a cast-iron convex side or shell, as indicated at D, which forms a vacant chamber, as indicated at E. And on the opposite side I fit a similar cast-iron convex shell, but considerably smaller, as indicated at F, forming a vacant chamber, as indicated at G. These two semi-shells, D and F, are to be secured to the main frame A A by a suitable number of screws passing through their flanges, as at a a and b b, which screws also pass through the outer portion, near the periphery of the two diaphragms, to secure their outer edges in a firm condition. And in these shells I make spaces in which rings or annular disks may rest when desired, as indicated at h h and i i, fig. 1. I make the valve-stem of cast iron, or any other suitable material, substantially of the form or shape indicated in section at H K L, fig. 1, with a suitable annular groove or recess, as indicated in section at e e, into which I fit a leather or any other suitable packing for the valve. And at suitable distances each way from this valve I make projecting shoulders on which the diaphragms are to rest, as indicated at K and L, and on the extreme ends I cut screw-threads to receive binding-nuts, over suitable washers, to hold the central part of the diaphragms in their places in all their relations to the other parts of the apparatus. I make the diaphragms M and N of prepared India rubber, or any other suitable material, of the proper sizes and thicknesses to operate as indicated.

Having made the several parts as before described, I slip the smaller diaphragm N on to the valve-stem at L, put on the washer, and turn on the nut, as indicated at e. I then pass the valve-stem through the smallest side opening in the frame, till the packing e e in the valve H rests on the valve-seat g g, and put on the shell F, securing it by suitable screws, which I pass through the flange at b b, &c., and the diaphragm N, so as to render the apartment G water-tight. I then put on the large diaphragm M, with its washer and nut, as indicated at d, put on the shell D, and secure it with screws which pass through the flange at a a, &c., and diaphragm M, so as to close or render the apartment E water-tight.

To use this apparatus I connect the induction pipe B with the supply pipe, and the eduction pipe C with a faucet (or other proper means) for using the water. I then let in the water, which, by pressing on the inner side of the smaller diaphragm N, will force the diaphragm into the vacant chamber or apartment G, so as to raise the valve from its seat and allow the water to pass into the larger apartment, as indicated by the dart, when it will press upon the larger diaphragm M, which will tend to force the diaphragm into the vacant chamber E, and to close the valve, when the compound effect, as to force, of the water passing in at B and out at C, will be inversely as the extent of yielding surface of the diaphragm N is to that of M, so that if a ring or annular disk, like fig. 2, should be placed in the larger shell, as indicated at h h, fig. 1, the difference of the yielding surfaces would be made less; but if placed in the smaller shell, as indicated at i i, the difference of the yielding surfaces would be made greater; so that by the original proportions of the diaphragms, and by the use of

ular disks of different widths, the difference between the force at the induction and eduction pipes may be made to vary to any desired extent. And for the convenience of emptying the regulator, (when the water is cut off back of it,) a screw, as P, tapped into the shell D, may be turned in, so as to open the valve, and to hold it open at any time, if desired.

What I claim as my invention, and desire to secure by Letters Patent, is—

1. The combination of the two diaphragms with the valve and its stem, when they are constructed, arranged, and fitted for use, substantially as herein described and set forth.
2. I claim the combination of a ring or annular disk with either of the diaphragms, when used to lessen the extent of the yielding surface of the diaphragm, substantially as herein described and set forth.

ISAAC JUDSON.
